(57) CLAIM

The ornamental design for a shampoo headrest, as shown and described.

DESCRIPTION

FIG. 1 is a perspective view of a shampoo headrest showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom view thereof.

The broken lines depicting portions of the shampoo headrest in the drawing are for illustrative purposes only and form no part of the claimed design.
